UNITED STATES PATENT OFFICE.

MICHAEL GREBNER, OF NEW YORK, N. Y.

IMPROVEMENT IN TOYS.

Specification forming part of Letters Patent No. **139,783**, dated June 10, 1873; application filed November 29, 1872.

To all whom it may concern:

Be it known that I, MICHAEL GREBNER, of the city, county, and State of New York, have invented a new and Improved Turn-table Toy; and I do hereby declare the following to be a full, clear, and exact description thereof, which will enable those skilled in the art to make and use the same, reference being had to the accompanying drawing forming part of this specification, in which drawing—

Figure 1 represents a vertical central section of this invention. Fig. 2 is an inverted plan of the same.

Similar letters indicate corresponding parts.

This invention has for its object to improve upon and render less complicated the turn-table toys now in use; and it consists in providing the traveling-platform on its top surface with carriers for engaging with and holding toys, and its bottom surface with a rack into which a gear-wheel meshes for the purpose of propelling said platform; it, the platform, being arranged and supported in a guideway formed in the rigid platform in the center of which is formed a socket for receiving a Christmas-tree, as hereinafter specified.

In the drawing, the letter A designates a platform which is supported by a frame B, and in which is formed a circular guide-way a, to receive a ring, b. On the bottom surface of this ring is formed a toothed rack, c, into which meshes a pinion, d, mounted on a shaft, e, that has its bearings in the frame B. On said shaft is secured a handle, f, so that by turning this handle the ring b is caused to travel round in its guide way. From the surface of the traveling-ring project carriers g, which are intended to catch in sockets h formed at the bottom parts of toys, such as

toy locomotives, toy cars, toy animals, or soldiers, or of toys of any desired description. If the toys are secured on the carriers, and a revolving motion is imparted to the ring b, the toys are caused to travel round the center of the platform A. In the center of said platform is secured a socket, C, for the reception of a Christmas-tree or any other articles of a similar nature; and if the same is secured in the socket and motion is imparted to the ring b the toys secured on said ring are caused to travel round the tree. If desired two or more concentric guide-ways may be arranged in the platform A, and by extending the shaft e, and mounting thereon several pinions, several rings fitted in said guide-ways may be caused to travel round in the same or in opposite directions.

I do not claim, broadly, a turn-table toy provided with a guide-way and a ring, when the latter is propelled by an arm connected with the same and made to impart motion to the ring by bevel-wheels arranged in the center of the stationary platform, for such is not my invention; but

What I claim as new, and desire to secure by Letters Patent, is—

The stationary platform A provided with the socket C to receive a Christmas-tree, and with the guide-way a to receive the traveling-ring b, carrying carriers g and the rack c, into which meshes the spur-wheel d driven by the shaft e, the whole constructed and arranged as herein shown and set forth.

This specification signed by me this 22d day of November, 1872.

M. GREBNER.
